DESIGN FOR A FILM SHOE FOR MOTION PICTURE APPARATUS OR THE LIKE

Otto R. Nemeth, Chicago, Ill., assignor to Products Development, Inc., Chicago, Ill., a corporation of Illinois

Application December 23, 1944, Serial No. 117,053

Term of patent 14 years

(Cl. D61—1)

To all whom it may concern:

Be it known that I, Otto R. Nemeth, a national of Czechoslovakia, residing at Chicago, in the county of Cook and State of Illinois, have invented a new, original, and ornamental Design for a Film Shoe for Motion Picture Apparatus or the like, of which the following is a specification, reference being had to the accompanying drawing forming part thereof.

Figure 1 is a perspective view of a film shoe for motion picture apparatus or the like embodying my design.

Fig. 2 is a top plan view of the film shoe.

Fig. 3 is a sectional view of the film shoe, taken substantially in the plane of line 3—3 of Fig. 2.

The essential features of the design reside in the parts shown in full lines.

I claim:

The ornamental design for a film shoe for motion picture apparatus or the like, substantially as shown and described.

OTTO R. NEMETH.
